US00D630199S

(12) **United States Design Patent**
Suzuki

(10) **Patent No.:** **US D630,199 S**
(45) **Date of Patent:** ** *Jan. 4, 2011

(54) **MOBILE PHONE**

(75) Inventor: **Shigeaki Suzuki**, Tokyo (JP)

(73) Assignee: **Sony Ericsson Mobile Communications Japan, Inc.**, Tokyo (JP)

(**) Term: **14 Years**

(21) Appl. No.: **29/311,419**

(22) Filed: **Mar. 11, 2009**

(30) **Foreign Application Priority Data**

Sep. 11, 2008 (JP) D2008-023400

(51) **LOC (9) Cl.** **14-03**

(52) **U.S. Cl.** **D14/248**

(58) **Field of Classification Search** ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3

See application file for complete search history.

(57) **CLAIM**

The ornamental design for a mobile phone, as shown and described.

DESCRIPTION

FIG. 1 is a perspective view of a mobile phone showing my new design;

FIG. 2 is a front elevational view thereof;

FIG. 3 is a rear elevational view thereof;

FIG. 4 is a top plan view thereof;

FIG. 5 is a bottom plan view thereof

FIG. 6 is a right side elevational view thereof; and,

FIG. 7 is a left side elevational view thereof.

The broken lines showing the remainder of the handset and the icons are directed to environment and are for illustrative purposes only; they form no part of the claim design. The dot-dash broken lines define the boundaries of, but are not included in, the claim design.

1 Claim, 7 Drawing Sheets
